SUPPORTING STAND FOR FLATIRONS

Helen Craig Davis, London, England

Application April 23, 1945, Serial No. 589,916
In Great Britain October 31, 1944

3 Claims. (Cl. 38—79)

1

This invention relates to hand irons of the kind which embody means to provide a stand for supporting the iron when out of use with its hot under face clear of said surface.

In irons of the above type as hitherto proposed the supporting means are lifted to permit the iron to be used by means which require for their operation pressure of the hand, finger or thumb, which pressure has to be maintained during ironing to prevent the supporting means from falling and trailing across the work. With such irons a conscious effort is required on the part of the operator to maintain the support in the raised position but as is well known the gripping of the iron handle during ironing is performed as an unconscious act and in certain instances is effected without downward pressure on the handle of the iron, in which case trailing of the supports across the work with consequential marking of or damage to the work will occur.

The object of the present invention is to avoid the above disadvantage.

Broadly the present invention consists of a hand iron of the type specified having means which operates automatically when the supporting means is raised to hold the same in said raised position during ironing.

Preferably the holding means of the present invention operates by friction and release is effected automatically by the weight of the iron as it is lifted by the operator.

The present invention is particularly applicable to irons of the kind in which the support consists of one or more pairs of arms pivoted to a plate which may be the pressure plate of the iron and which are turned to the raised position clear of the underface of the iron by means associated with the handle of the iron. For example the handle may consist of two portions one of which is pivoted and connected by its free end to the supporting arms which are then raised by the operator squeezing the handle so as to turn the pivoted portion about its pivot. Alternatively the lifting of the support may be performed by the operator pressing his thumb or finger against a button arranged in suitable juxtaposition to the handle.

In a preferred embodiment of the present invention the supporting arms are lifted by a squeezing action on the part of the operator on a pivoted section of the handle disposed above a fixed handle and they are held in the raised or lifted position by the frictional engagement of a resilient blade member which is fixedly anchored to a suitable stationary part of the iron and a movable member connected to, and actuated by, the movable handle.

With this arrangement, when the handle is gripped the pivoted section of the handle is forced towards the fixed part of the handle and

2

this serves to turn the supporting arms about their pivots to the raised position.

The frictional engagement between the protuberance and the spring blade is sufficient to hold the supporting arms in the raised position but when the iron is lifted by the pivoted section of the handle the weight of the iron acts to displace the movable member connected to the handle by overcoming the frictional hold of the spring blade, and forcibly turn the supporting arms into the lowered or supporting position.

In a further embodiment where the supporting arms are turned through a vertical connecting rod attached to the handle and a crank on the transverse pivot of the arms the same may be held in both the raised and lowered positions by a blade spring pressing on the crank.

In one such arrangement the vertical connecting rod is forked at its lower end and engages opposite sides of a central crank the intermediate portion of which is engaged by the spring.

In a further embodiment the transverse pivot rod of one of the pairs of supporting arms is provided with a ratchet or other toothed wheel or segment, the teeth or slots in which are engageable by a spring pawl to hold the supporting arms in both the lowered and raised positions. The arms are freed by withdrawing the pawl out of engagement with the ratchet or other device by means operated either from the handle or a separate lever or button arranged suitably adjacent to it.

In a still further embodiment the supporting arms may be retained in the raised position by means of a light coil spring which is anchored at one end to a fixed part of the iron and at its free end is attached to the aforesaid crank.

To prevent the arms from being laterally displaced so as to foul the sole plate of the iron the connecting rod which engages the crank is guided or supported along one or both sides such as by disposing the same within a groove or slot in the pressure plate.

In order that the invention may be clearly understood and carried into effect several practical examples will now be described by aid of the accompanying drawings in which:

Fig. 1 is a vertical section through an iron according to a preferred embodiment of the present invention and Fig. 2 is a top plan view of the same with the cover plate removed.

Figs. 3 and 4 are similar views of a further embodiment in which the frictional hold for maintaining the supporting arms in the raised position is afforded by a blade spring pressing upon a crank in the transverse pivot of the supporting means.

Fig. 5 is a detail view illustrating the use of a coil spring as the means for holding the supporting arms in the raised position. Fig. 6 is

also a detail view showing one manner of using a spring-pressed ball detent as the holding means as applied to the example illustrated in Fig. 1.

In the flat irons according to the two embodiments illustrated in Figs. 1 and 2 and 3 and 4, 1 is the pressure plate, 2 the sole plate, 3 the supporting legs, 4 the stirrup or U-shaped handle support, 5 the movable portion of the handle and 6 the fixed portion thereof. Referring now particularly to the iron illustrated in Figs. 1 and 2 the movable portion 5 of the handle is pivoted at its forward end to the front upright 7 of the stirrup 4 as at 8 so that its near end is free to move up and down in relation to the back upright of the stirrup which acts as a support for the fixed handle portion 6 and engages in a recess 10 in the underside of the handle portion 5, such recess being substantially the same width as the upright so that the handle is held by it against lateral displacement. By enclosing with his hand both the movable and fixed portions of the handle and applying a squeezing action the operator is enabled to depress the rear end of the handle portion 5 and this motion is utilised to raise the supporting legs 3. The means for this purpose which are illustrated in the drawings comprise a connecting member 11 which at its upper end is pivoted as at 12 to the rear end of the movable handle portion 5 within the recess 10 and at its lower end is similarly attached to one crank portion 13 and a crank shaft 14. This crank shaft is pivotally mounted by its ends within a recess at the back of the pressure plate 1 of the iron and its other crank 15 is connected to a crank arm 16, by means of a horizontal coupling link 17. The crank arm 16 forms part of a transverse portion connecting the two supporting legs 3. These legs reside one on each side of the iron on the outside of the casing 18 and the sole plate 2, said transverse portion forming the pivot for said legs, and a slot 19 in the upper surface of the pressure plate 1 the bearing for such pivot. By the means thus described depression of the rear or free end of the handle portion 5 turns the legs 3 upwards to the dotted line position shown in Fig. 1. For the purpose of the present invention it is necessary that these legs shall be held automatically in this raised position whilst the iron is in use and the means for this purpose which is illustrated in Fig. 1 consists of a blade spring 20 which is secured at its lower end to the upper surface of the casing 18 and extends upwards between the connecting member 11 and the stirrup upright 9 with its upper end 21 contacting the opposing face of the connecting member with a pressure sufficient to hold the supporting legs in the raised position.

To lower the legs the operator lifts the iron by the movable portion only of the handle with the result that the weight of the lower part of the iron overcomes the frictional resistance of the blade spring 20 and in dropping pulls the supporting legs round to the supporting position shown in full lines in Fig. 1.

To prevent the leg 3 from fouling the side of the sole plate 2 as a result of excessive lateral movement, such excessive movement is checked by arranging that the coupling link 16 shall move within a longitudinal slot 22 in the upper surface of the pressure plate, said slot being narrow enough to constrain the link from undue lateral movement.

In the embodiment illustrated in Figs. 3 and 4 the whole of the mechanism for raising and lower-

ing the supporting legs and the means for holding the same frictionally in the raised position is disposed on top of the casing 18 and such mechanism and means comprises a bell crank 5 lever comprised of two parallel side plates 23 which are mounted to pivot about a pin 24 carried by a fixed bracket 25 having a bent foot 26 by means of which it is bolted to the upper face of the stirrup 4 by one of its holding bolts 27. The upper corner of this bell crank lever is connected to opposite ends of a crank 28 on the transverse pivot portion of the supporting legs by means of a pair of laterally spaced connecting links 29.

The means for holding the supporting legs frictionally in the raised position consists of a flat blade spring 30 one end of which is secured or anchored by the forward stirrup retaining bolt 31 with the opposite or free end pressing down upon the crank 28 between the connecting links 29.

20 The member comprising the supporting leg 3 is pivotally mounted upon a stamped metal bed-plate 32 which is affixed to the upper surface of the casing 18 by the securing bolts 27 and 31. 25 The supporting legs in this example are raised and lowered as in the previous example.

In lieu of the blade spring 30 in Figs. 3 and 4 a coil spring may be used. This alternative is illustrated in Fig. 5 where the coil spring, indicated 30 by the numeral 33, is shown as being anchored at one end by the securing bolt 31 with the other end attached to the crank 28 intermediate the two connecting links 29. The tension of this spring 33 must of course be sufficiently light so as 35 to be overcome by the weight of the iron when the same is lifted by the movable portion 5 of the handle.

In a further alternative friction holding means, that is applicable to the embodiment illustrated 40 in Fig. 1 a spring pressed ball detent may be used. Such an alternative is illustrated in Fig. 6 where 34 is the spring pressed ball detent. This is shown as being enclosed in a tubular casing 35 that is 45 sunk into the rear end of the fixed handle portion 6. The ball is adapted to be engaged by a depression, hole or the like in the length of the connecting member 11.

What I claim is:

1. A hand iron comprising a main body; a stirrup rigidly fixed thereto; a first handle portion rigidly fixed to said stirrup; a second handle portion pivoted to one upright branch of said stirrup, said second handle part being movable with respect to said first one between an adjacent and spaced positioned relationship by effect of the weight of said main body, stirrup, and first handle portion, when the iron is suspended by said second handle portion; a link member pivoted to said second handle portion and movable therewith with respect to said main body; a first crank shaft journalled in said main body and rocked by the motion of said link member between two extreme positions corresponding to said adjacent and spaced positioned relationship of said second handle portion with respect to said first handle portion; a second crankshaft journalled in said main body and carrying support extensions, said second crankshaft being rockable between two extreme positions of said support extensions, a lowered operative and a raised inoperative position; link means connecting said first and second crankshafts whereby the rocking motion is transmitted from the former to the latter; and spring means secured to said stirrup and 70 frictionally engaging said link member, whereby 75

sufficient resistance is created to the motion of said link member to prevent the same from occurring by effect only of the moment of said support extensions and crankshafts about their journals.

2. A hand iron comprising a main body; a stirrup rigidly fixed thereto; a first handle portion rigidly fixed to said stirrup; a second handle portion pivoted to one upright branch of said stirrup, said second handle part being movable with respect to said first one between an adjacent and a spaced positioned relationship by effect of the weight of said main body, stirrup, and first handle portion, when the iron is suspended by said second handle portion; a link member pivoted to said second handle portion and movable therewith with respect to said main body; a first crankshaft journaled in said main body and rocked by the motion of said link member between two extreme positions corresponding to said adjacent and spaced positioned relationship of said second handle portion with respect to said first handle portion; a second crankshaft journaled in said main body and carrying support extensions, said second crankshaft being rockable between two extreme positions of said support extensions, a lowered operative and a raised inoperative position; link means connecting said first and second crankshafts whereby the rocking motion is transmitted from the former to the latter, said link means being housed in slots in said main body to control the lateral displacement of the same

and thereby of both aforementioned crankshafts and of said support extensions; and spring means secured to said stirrup and frictionally engaging said link member, whereby sufficient resistance is created to the motion of said link member to prevent the same from occurring by effect only of the moment of said support extensions and crankshafts about their journals.

3. A flat iron according to claim 1, wherein the relative position of the center of gravity of the iron and the center of the support extensions is such that when these latter are in their extreme operative position the weight of the iron and the support reaction give rise to a couple which tends to force said support extensions further towards and beyond said extreme operative position.
